(57) **CLAIM**

The ornamental design for a hand grip with ring, as shown and described.

DESCRIPTION

FIG. 1 is a perspective view of a portion of a hand grip with ring, it should be understood that the stippled surface shading represents a surface having a contrasting color relative to the color of the remainder of the ring;

FIG. 2 is a top view of said portion of the hand grip with ring of FIG. 1;

FIG. 3 is a bottom view of said portion of the hand grip with ring of FIG. 1;

FIG. 4 is a front view of said portion of the hand grip with ring of FIG. 1;

FIG. 5 is a back view of said portion of the hand grip with ring of FIG. 1;

FIG. 6 is a left view of said portion of the hand grip with ring of FIG. 1; and,

FIG. 7 is a right view of said portion of the hand grip with ring of FIG. 1.

The broken lines shown in the drawings are for illustrative purposes only and form no part of the claimed design.
